UNITED STATES PATENT OFFICE.

ERD V. CROWELL, OF LOS ANGELES, CALIFORNIA, ASSIGNOR OF ONE-HALF TO THE
GUIBERSON CORPORATION, OF DALLAS, TEXAS, A CORPORATION OF DELAWARE.

COMBINED CASING HEAD, OIL SAVER, AND TUBING LANDER.

Application filed February 20, 1923. Serial No. 620,293.

This invention relates to a combined casing head, tubing oil saver and landing head especially adapted for use in flowing oil or gas wells, where the element of invention 5 resides not alone in the particular design of the elementary parts, but in their adaptability to produce a desirable and practical result by their combined, individual and successive use.

10 Briefly stated an important object of the invention is to provide a combined casing head, tubing oil saver and landing head by means of which a tubing or any cylindrical tool may be introduced into the casing of a flowing oil or gas well and landed without 15 the escape of oil or gas at the mouth of the well.

Also the invention forming the subject matter of this application aims to provide 20 a quick, convenient and positive means for temporarily anchoring the tubing to the casing head while additional joints of tubing are being screwed onto the exposed portion of the tubing, there being means to provide 25 a temporary seal between the tubing and the casing head during the descent of the tubing or while the same is temporarily held in a set position.

Further the invention aims to provide a 30 quick, convenient and positive means for permanently sealing the annular space between the casing head and the tubing after the tubing has been landed.

Other objects and advantages of the invention will be apparent during the course 35 of the following description.

In the accompanying drawing forming a part of this application and in which like numerals are employed to designate like 40 parts throughout the same,

Figure 1 is a vertical sectional view through one major application of the invention, the tubing oil saver being in position on the casing head with the packing rubbers thereof in engagement with the tubing so as to effect a temporary and yieldable seal between the tubing and the casing head.

Figure 2 is a vertical sectional view through the other major application of the invention, the landing head being shown in operative position on the casing head while the tubing oil saver has been detached from the casing head.

Figure 3 is a vertical sectional view

through all parts assembled, as a combination, the landing head being shown in operative position on the casing head, having been lowered to position through the tubing oil saver, the packing rubbers of the tubing oil saver being shown in their inoperative 60 positions preparatory to the removal of the tubing oil saver from the casing head.

Figure 4 is a partial perspective view of the slips.

Figure 5 is a perspective view of a spider 65 embodied in the invention.

Figure 6 is a perspective view showing a section of the housing lid.

Figure 7 is a perspective view of another 70 section of the housing.

Figure 8 is a fragmentary perspective of the housing rubber cage.

Figure 9 is a side elevation of the improved tubular packing clamp, forming a 75 part of the landing head feature.

Figure 10 is a perspective of one of the sections of the tubular packing clamp.

Figure 11 is a perspective of one portion of the tubular packing.

Figure 12 is a perspective of one portion 80 of the tubular packing annulus.

Figure 13 is a perspective of the other portion of the tubular annulus.

Figure 14 is a perspective view of a portion 85 of the housing rubber packing section.

Figure 15 is a perspective of a packing gland embodied in the invention.

Figure 16 is a perspective view of the casing head and its several connections.

Figure 17 is a perspective partly in section of the casing head rubber.

In the drawing wherein for the purpose of illustration is shown a preferred embodiment of the invention, the numeral 5 designates a casing of the usual and well known construction, the upper end of which has threaded engagement with a casing head 6. The usual lead lines 7 extend from the casing head 6 and discharge the oil from the casing into a tank or the like.

The invention forming the subject matter of this application is provided with simple means whereby the tubing 8 may be introduced into the well casing with a minimum loss of gas and oil and with the fire hazard reduced to a minimum.

When the tubing is being lowered into the well casing, the oil saver housing 10 is

mounted on the upper end of the casing head and the depending flange 12 of the same receives the upper portion of the casing head. The tubing oil saver housing, is composed of a pair of semi-elliptical sections, the edges of which are formed with ears 14 for the reception of fastening bolts by means of which the sections may be connected. Figure 1 illustrates that the inner side of each depending flange 12 is formed with an inwardly extending projection 15 received in an annular groove 16 in the adjacent portion of the casing head, and a packing 17 carried by the inwardly extending rib or projection 15 provides a gas and liquid tight connection between the housing 10 and the casing head.

Figure 1 illustrates that the inwardly extending projection 15, when received in the groove 16 also securely connects the housing to the casing head and prevents gas pressure from blowing the housing off.

Figure 1 also illustrates that the casing head has its upper portion interiorly enlarged to provide an annular shoulder 20 which supports a packing 21 or what might be said to be a casing head rubber. A packing gland 24 of tubular formation surrounds the tubing and is provided with a laterally projecting flange 25 which contacts with the casing head rubber 21 whereby to provide a tight connection between the gland and the casing head.

When preparing to introduce the tubing into the well a plurality of packing rubbers 30 are arranged about the tubing and are held in position by means of a packing holder 31 composed of a pair of semi-circular sections. It might be stated that the packers 30 are composed of semi-circular sections and are held in position by means of the inwardly directed ribs 33 of the packing holder 31.

Figure 1 illustrates that the sections of the packing holder 31 are provided with outwardly projecting members 35 having their under sides open for the reception of the heads 36 of adjusting screws 37. The adjusting screws 37 are threaded through the housing 10 and are provided with handles 38 by means of which the screws may be rotated. During the descent of the tubing the packers 30 provide a yieldable seat between the tubing and the housing 10. When the couplings which join the sections of the tubing pass through the housing 10 the rubber packers 30 expand so as to permit of the free movement of the couplings. Therefore, the packers 30 of which there may be three or any desired number provide a convenient means for preventing the escape of oil and gas through the housing 10 during the descent of the tubing and while the tubing is temporarily brought to rest for the purpose of adding a section or for the

pose of detaching a section. This insures the production of oil during the descent of the tubing.

When it is desired to temporarily hold the tubing in a set position for the purpose outlined, slips 60 may be inserted into the tapered opening of a spider 61 and the slips will, of course, be tightly engaged with the tubing.

Figure 1 illustrates that the spider 61 is provided with a laterally projecting flange 62 which is engaged with the upper side of the housing cap or lid 64. It might be stated that the cap 64 is composed of semi-elliptical sections the meeting portions of which are connected by fastening devices or the like. The cap 64 is provided with an upstanding annular flange 67 having downwardly and inwardly extending set screws 68 which engage the flange 62 and thereby hold the spider in position. Of course, when it is desired to release the spider for a purpose to be fully and hereinafter described the set screws may be loosened.

When the tubing has been lowered to the proper position in the well the packers 30, the cap 64 and the housing 10 may be removed and an annular packing 70 arranged between the packing gland 24 and the tubing whereby to form a seal. The packing 70 is connected to the lower end of a tubular clamp 71 by means of a plurality of fastening devices 72. The fastening devices which are in the nature of bolts are extended entirely through the packer 70. When the packer is in position within the gland 24, the annulus 74 upon the lower end of the same is engaged with the inwardly projecting shoulder 75 of the packing gland. When the packer 70 is compressed the upper portions of the fastening bolts 72 and the nuts thereon are received in slots 76 formed in the tubular clamp 71.

Of course, preparatory to placing the clamp 71 in position the spider 61 is elevated to the position illustrated in Figure 3 and the lower side of the same is engaged with the enlarged upper end 80 of the clamp 71. It might be stated that the clamp 71 is composed of a pair of semi-circular sections as illustrated in Figure 9. In Figure 10 it is shown that the edges of the sections are formed with ears 81 adapted for the reception of fastening bolts or the like. Particular attention is called to the fact that all important parts of the tubing oil saver and the landing head, as shown assembled in Figures 1 and 3 are made in separate detachable sections secured together by means of bolts, nuts or other fastening devices, thus permitting them to be assembled about the tubing or to be detached without having to slip them over the tubing, a feature very important to the successful performance of the work.

Figures 6 and 7 illustrate that the upper portion of each section of the housing 10 is provided with laterally projecting flanges 68 which are adapted to be received in the grooves 66 of the lid section 64 whereby the lid section is securely and positively attached to the housing.

With reference to the foregoing description taken in connection with the accompanying drawings it will be apparent that this invention resides in the novel combination of major parts by means of which the tubing may be landed, and by means of which a substantial saving in oil and gas is brought about.

In operation the tubing oil saver is assembled upon the casing head, the packing gland and casing head rubber are positioned in the casing head as shown in Figure 1, the tubing 8 is started in the well and the housing rubbers 30 are adjusted tightly up against the tubing as shown. When the housing rubbers 30 are thus jammed tight up against the tubing by means of the operating screws 37 it is evident that the rubbers make a gas tight seal between the housing sections 10 and the tubing 8. Therefore the only avenue of escape for oil and gas is out through the lead lines 7 where the oil can be conserved and is prevented from reaching the derrick floor above where the men are at work. These housing rubbers 30 are of such ample diameter that when they are jammed tight up against the tubing to form a positive seal they are yieldable to such an extent that the tubing can be raised or lowered through them without interrupting the protection.

The spider 61 is temporarily positioned in the lid section 64 and held securely in position by means of set screws 68. The slips 60 are machined so as to fit the tapering bore of the spider 61 and the weight of the tubing serves to make the slips more securely grip the tubing. With the spider and slips thus positioned in the lid sections 64 they furnish means for intermittently anchoring the tubing as it is desired to add sections while the tubing operation is in progress.

After the full string of tubing has thus been run into the well and it is desired to land it, the housing rubbers 30 are left clamped tight against the tubing 8 until the landing head feature is assembled upon the tubing and ready to be made operative. The set screws 68 are loosened to permit the spider 61 to be elevated on the tubing several feet while the weight of the tubing is suspended from the derrick by the elevators in the usual manner. Then the landing head assembled as shown in Figure 9 is arranged about the tubing 8, under the spider 61, after which the spider 61 is allowed to rest on top of the tubular clamps 71 and the slips 60 are dropped to place within the spider 61. Therefore the tubing is securely attached to

the spider 61; and the spider, in turn, is resting on top of the tubular clamps 71. It will be seen that when the weight of the tubing is allowed to settle the tubular clamps 71, the spider 61 and the slips will move down through the oil saver, to final position, as illustrated in Figure 3.

Of course as the landing head is being moved through the oil saver as a result of the descend of the tubing the housing rubbers 30 are moved out of the way back in the housing section by means of operating screws 37. As previously stated the housing sections are semielliptical in shape so as to provide spaces to receive the packing members when moved to their inoperative positions.

When the landing head has been brought to final and operative position as shown in Figure 3 the oil saver has served its purpose and may be detached from the casing head leaving the parts in the position shown in Figure 2.

In Figure 2 the landing head feature is shown in operative position, the tubing is supported by the spider and slips and the weight of the tubing 8 working through the spider and slips and the tubular clamps 71 has made the rubbers 21 and 70 operate. That is to say, the weight of the tubing is transmitted through the members 71 and is borne by the rubbers 21 and 70 whereby the rubbers 21 have made a seal between the casing head 6 and the gland 24, and the rubbers 70 have made a seal between the tubing 8 and the gland 24 to prevent the escape of oil or gas.

Figure 3 shows the simultaneous assembly of the tubing oil saver and the landing head upon the casing head, one of the distinctive features of the combination offering an important advantage, for as must be remembered, the tubing oil saver serves one purpose while the landing head serves a different purpose, yet their combined and successive use is necessary to answer the requirements of the tubing operation. The prime object of the present invention is to provide protection against the escape of oil or gas, except through the lead lines 7, while the tubing operation is in progress, whether the operation be that of running the tubing or landing it. To do this it is necessary to provide a tubing oil saver assembled as shown in Figure 1 and a landing head assembled as shown in Figure 2, particularly adapted to their individual purposes and capable of being expeditiously interchanged under the conditions encountered in their use. The novelty of the invention resides, therefore, not alone in the particular design of the individual parts but in their adaptability to combination to answer the requirements of their purpose.

In carrying out the objects of the invention the housing rubber cage shown in Fig-

ure 8 is a semi-circular cage for the housing rubbers 30 and the rubbers are attached therein to the rib sections 33 by means of bolts or other fastening devices, this feature 5 being illustrated in Figure 1. The cages 31 have upstanding lugs or gudgeons 34 which contact with the lid sections 64 in assembly as shown in Fig. 1. It is the purpose of these lugs 34 to prevent the housing rubbers 10 30 from tilting or buckling as they are jammed tight up against the tubing 8, as shown in Figure 1. For the purpose of illustration the housing rubbers 30 are shown clamped tight up against the tubing 8 in 15 Figure 1. It is evident that the expansion of the rubbers 30 must be limited so that a seal is made between the tubing 8 and the housing section 10. As the housing rubbers 30 are jammed tight up against the tubing 8 20 as shown in Figure 1 the lower rubber makes a seal with the bottom of the housing 10 as well as with the tubing 8, while the upper rubbers add strength and make a seal with the sides of the housing section 10. Thus as 25 the rubber cage sections 31 are adjusted up against the tubing 8 as shown in Figure 1 the rubbers 30 are forced to make a positive but yieldable seal between the tubing 8 and the housing sections 10 through which 30 the tubing 8 may be operated.

Having thus described the invention, what I claim is:—

1. The combination of a casing head, a tubing oil saver associated therewith, and a tubing support extending through the oil saver and mounted on the casing head.

2. The combination with a casing head, of an oil saver supported by said head, a packing gland received in said head, and a packing arranged between said gland and head.

3. The combination of a casing head, a gland associated with the head, a tubular clamp having a packing received in said gland, and a tubing supporting means carried by said tubular clamp, and an oil saver surrounding the clamp between the tubing supporting means and said packing.

4. A tubing support comprising a tubular body having tubing engaging means, and a compressible packing having attaching members slidably connected to said body.

5. The combination with a casing head, of a tubing oil saver mounted on the casing head, an elongated tubing landing member extending through the oil saver and supported by the head, a spider mounted on the upper portion of the tubing landing member, and slips received in said spider and adapted to engage a tubing.

6. The combination with a casing head, of a tubing oil saver mounted on the casing head, an elongated tubing landing member extending through the oil saver, the casing head having a receiving portion for supporting the landing member whereby the oil

saver may be removed, and compressible means sustaining the weight of tubing carried by the landing member for effecting a fluid tight connection between the tubing landing member and its support.

7. The combination of a casing head, a gland received in said head, and a tubular clamp having a packing movably connected thereto and received in said gland, said clamp being provided with tubing supporting means above said oil saver.

8. The combination of a casing head, a housing consisting of sections having means whereby the same may be detachably connected, a packing holder arranged within the housing and consisting of a plurality of sections having inwardly directed flanges, arcuate packings carried by said flanges and adapted for yieldably engaging a well tubing whereby to permit of the passage of the 85 couplings on the tubing, means whereby the tension of the packings may be varied, a packing gland received in said head and a tubing support surrounding the tubing and having a packing received in said packing 90 gland, and means associated with the upper portion of the tubing support to limit the descent of the well tubing.

9. The combination with a casing head, of a packing gland associated therewith and adapted to receive a well tubing, a tubing support consisting of a pair of semicircular sections surrounding the tubing and having the lower portions provided with a packing received in said gland, a spider mounted on 100 the upper end of said clamp, and slips received in said spider and adapted for engaging a well tubing, and an oil saver adapted to be applied to said head and surround said clamp.

10. The combination of a casing head, of a packing gland associated therewith and having a shoulder, a packing received in said gland and engaging said shoulder, a packing clamp of tubular formation having its 110 lower portion formed with a plurality of longitudinal slots, and fastening devices extending through said packings and into said slots whereby the packing may contract.

11. The combination of a casing head, a 115 packing gland associated therewith and having a shoulder, a packing received in said gland and engaging said shoulder, a packing clamp having its lower portion formed with longitudinal slots, fastening devices extending through said packing and into said slots whereby the packings may contract, a spider mounted on said clamp, and slips received in said spider and adapted for engaging a well tubing whereby to limit the downward movement of the same, said packing clamp being urged downwardly by the weight of the tubing for expanding said packing.

12. The combination of a packing gland,

a packing received therein and adapted to provide a liquid and gas-tight connection between the gland and the tubing, a tubular member having its lower portion provided 5 with slots, fastening devices extending through said packing and the lower portion of said tubular member, said fastening devices being freely received in said slots whereby the packing may contract, a spider 10 engaged with the upper end of said clamp, and slips received in said spider.

13. The combination of a packing gland, a packing received therein and adapted to provide a liquid and gas-tight connection 15 between the gland and the tubing, a tubular member having its lower portion provided with slots, fastening devices extending through said packing and the lower portion of said tubular member, said fastening 20 devices being freely received in said slots whereby the packing may contract, a spider engaged with the upper end of said clamp, slips received in said spider, and a tubing 25 wall saver arranged about the tubular member.

14. The combination of a packing gland, a packing received therein and adapted to provide a liquid and gas-tight connection between the gland and the tubing, a tubular member having its lower portion provided 30 with slots, fastening devices extending through said packing and the lower portion of said tubular member, said fastening devices being freely received in said slots 35 whereby the packing may contract, a spider engaged with the upper end of said clamp, slips received in said spider, an oil saver arranged about the tubular member, and a casing head adapted for supporting said 40 gland and said oil saver.

15. The combination with a casing head,

of a tubing oil saver, and a landing head operating vertically through the oil saver, the casing head having separate means for individually supporting the oil saver and the landing head, whereby either the oil saver or the landing head may be mounted on the casing head or removed therefrom without interference from each other. 45

16. In a device of the character described, 50 a tubing oil saver comprising housing and lid sections releasably attached to each other and to the casing head in assembly, a tubing anehoring means consisting of spider and set 55 of slips releasably attached to the lid sections, a packing head arranged within the housing sections consisting of a pair of semi-circular sections having their inner sides formed with supports, packers carried by 60 said supports, and adjusting devices carried by said housing sections and engaged with said sections whereby the packers may be adjusted with relation to the tubing.

17. The combination with a well casing, 65 a casing head arranged thereon, a tubing extending through said casing and casing head, a tubing oil saver comprising housing and lid sections releasably secured to each other and to the casing head in assembly, a tubing 70 anchoring means consisting of a spider and set of slips releasably secured to the lid sections, a packing head arranged within the housing sections consisting of a pair of semi-circular packing sections operatively 75 attached to the housing sections so designed and proportioned that the packing sections may be adjusted against the tubing so as to form a gas-tight seal or may be made to recede back from and into the housing sections so as to open the full radial area of the 80 casing.

ERD V. CROWELL.
